FIG. 3

FIG. 4

Corydon W. Sexton,

By

Frank L. Morris
Attorney

UNITED STATES PATENT OFFICE.

CORYDON W. SEXTON, OF CHARLOTTE, NORTH CAROLINA.

HEATING APPARATUS.

Application filed April 18, 1922. Serial No. 554,979.

To all whom it may concern:

Be it known that I, CORYDON W. SEXTON, a citizen of the United States, residing at Charlotte, in the county of Mecklenberg and 5 State of North Carolina, have invented new and useful Improvements in Heating Apparatus, of which the following is a specification.

This invention relates to heating apparatus for buildings and proposes the construction of a heater of the heated air type which is adapted to be installed on the same floor or level as the rooms to be heated and will positively create and maintain circulation of air by drawing cold air from a remote point in the room which is to be heated, or from another room or rooms, through a properly proportioned conduit, and radiating warm air to be carried by convection to 20 the point or points from which the cold air is exhausted.

One of the objects of the invention is the construction of a heater which is double walled on all sides, with an air space enclosed between the walls, so as to efficiently gather all the heat radiated from the interior thereof, as well as to render the heater safe from the standpoint of fire risk.

Another object of the invention is the provision of an inner combustion box, one portion of which is constituted as a flue chamber by being provided with a plurality of air flues communicating at their opposite ends with the air space between the double 35 walls at the top and bottom of the heater and the front portion of which includes a fire pot of substantially the same width as the combustion box and being unrestrictedly open at the top and in communication with 40 said flue chamber.

Still another object of the invention is the provision of a transverse partition wall lying in a vertical plane at an intermediate portion of the flue chamber and provided 45 with a permanently open avenue of communication below its lower edge between the adjacent parts of said flue chamber, and a damper-controlled opening near its upper end, the smoke pipe being located on the 50 opposite side of said partition wall from the fire pot.

Still another object of the invention is the provision of the double walled air chamber surrounding the combustion box, and having 55 cold air conduits leading from remote points to the lower portion thereof and also hav-

ing perforations in its upper wall communicating with the atmosphere, whereby air is supplied to said air chamber to be heated therein, and discharged therefrom.

Still another object of the invention is the provision of a humidifier in the heated air chamber, equipped with signalling means for indicating the level of liquid within said humidifier.

With the above and other objects in view, my invention consists in the improved heating apparatus illustrated in the accompanying drawings, described in the following specification, and particularly claimed, and in such variations and modifications thereof as will be obvious to those skilled in the art to which my invention relates.

In the drawings accompanying and forming a part of this specification, and wherein the preferred embodiment of my invention is illustrated:

Figure 1 is a side elevation in cross section showing the construction of my improved heating apparatus.

Figure 2 is a transverse cross section taken along the line 2—2 of Figure 1.

Figure 3 is a front view, partly in elevation and partly in cross section, taken along the line 3—3 of Figure 1.

Figure 4 is a cross sectional view taken along the line 4—4 of Figure 1.

Referring now in detail to the several figures, the numerals 1 and 2 represent, respectively, the front and back outer walls of the heating apparatus which are joined to the outer side walls 3 and 4, the shape of the outer casing thus formed being rectangular. These walls are preferably made of a heavy grade of sheet metal and are secured to the bottom and top walls 5 and 6, respectively. This casing surrounds an inner casing or combustion box which is likewise formed of four vertical side walls 7, 8, 9 and 10 which are joined at the top and bottom to the headers 11 and 12, and held in place by the stay bolts 56. The combustion box is spaced from the outer casing on all sides, being supported from the bottom thereof upon the upwardly extending lugs 13 and 14 which are preferably made integral with the outer bottom wall 5. The front walls 1 and 7 of the outer casing and combustion box are perforated with aligned rectangular openings in which is seated the frame 15 of the fuel door 16 hinged at its lower edge 52, and with another pair of

aligned openings in which is fitted a frame 17 which hingedly carries a sliding door 18. The lower wall of the frame 15 slopes downwardly providing a chute for the fuel automatically delivering the same to the firepot. The walls 1 and 7 are also provided with elongated aligning apertures which are separated from the air space between said walls by means of a suitable frame 19. This frame has a flange 20 which bears against the outer face of the front wall 1. The opening thus formed is closed by the ash door 21, which is hingedly secured to the outer front wall 1 and carries the draft damper 22. A clutch damper 53 operating on a threaded stem 54, is mounted on the fuel door 16. The inner and outer back walls are provided with aligned apertures at their lower ends in which is fitted the frame 24 of the clean-out door 25. A similar clean out door 53 is located at the back of the ash pit. A flanged thimble 26 is secured around the edge of a smoke aperture 27 in the top header 11 and passing through an aperture in the outer top wall 6 telescopes into the smoke pipe 28. It will thus be observed that the air space within the outer casing and surrounding the combustion box is sealed in smoke-tight manner with respect to all of the orifices opening into the combustion box. The outer bottom wall 5 is supported in spaced relation to the floor by the stove legs 23 which are of the usual construction, and from the bottom wall 5, on opposite sides of the heater, rise braces 57, carrying the foot rests 58.

The cold air conduits 29 and 30, which are here shown as two in number but may be, in practice, of any desired number, communicate with the air space between the inner and outer casings by means of the openings 31 and 32, in the bottom wall 5, and lead to points in the building or suite of rooms to be heated and from which the cold air is taken. The outer top wall 6 is perforated permitting the escape of the heated air from the surrounding air chamber into the atmosphere.

A tank 33 is secured in any suitable manner within the air space between the inner and outer back walls and a spigot 34, by means of which said tank may be drained, is connected to the lower portion of said tank. A float 35 is located within said tank 55 and is provided with a stem 36 extending through a small aperture 37 in the top wall 6, for reciprocation therethrough. At the upper end of said stem externally of the heating apparatus is a visual signalling element 38 which is preferably of a bright color to readily engage the attention. This signalling device responds to conditions of liquid level within said tank. A filler cap 60 39 threadedly engages an aperture in the upper top wall 6 adjacent to the upper end

of said tank, through which the latter may be supplied with water from time to time when necessary.

Within the forward portion of the combustion box is the fire pot which extends substantially the entire width of the combustion box and is segregated in part from the flue chamber, hereinafter to be described, by means of the transverse cast iron wall 40 which makes a tight fit with the bottom and sides of said combustion box but terminates short of the top thereof. The fire pot is lined with the fire-brick 41, best shown in Figures 1 and 2, and is provided with a dumping grate 42 which may be of any desirable type. The grate shank 43 projects through aligned apertures in the side walls of the heating apparatus and is formed on its outer end with a shaker-hold 44. Below the grate is an ash pit 45 in which is a receptacle 46 having a sufficient capacity to permit infrequent removal of the ashes. The sliding door 18 and the fuel door 16 communicate with the fire pot above the grate, the latter being large enough to permit the introduction of chunks of wood of considerable size into the fire pot.

There is no top to the fire pot nor do the walls of the latter converge so as to constrict the opening communicating with the combustion box, so that the flames and hot gases from the fire pot are perfectly free to issue forth above the wall 40 into the space surrounding the air flues 47. Said flues are of the usual tubular construction and extend from apertures in the top header 11 to aligned apertures in the bottom header 12 and engage flanges 48 which surround said apertures, thus making gas-tight connection with said headers. Said flues are arranged in a plurality of banks or rows, as is plainly shown in Figure 2. Intermediate these banks is disposed a partition 49 which is secured to the top header and side walls of the combustion box and extends within a reasonably short distance of the lower header, leaving a space between its lower edge and said lower header for the passage therethrough of gases on their way to the smoke pipe 28. The upper part of the partition 49 is constructed with a rectangular opening 50 extending across the major portion of the width thereof, which opening is controlled by a damper 51 which is hingedly supported upon said partition 49 and operated by a rod 52 secured thereto and extending outside of the heater as shown in Figure 4.

When it is desired to increase combustion the damper 51 is opened so that the draft from the fire pot will follow a direct path to the smoke pipe 28. When it is desired to obtain maximum heating efficiently the damper 51 is closed and the products of combustion are compelled to follow a tor-

tuous path down past the lower edge of the partition 49 and then up toward the smoke pipe.

By the arrangement and construction of my improved heating apparatus I have perfected a heating device in which uniform distribution of heat is assured by blanketing the entire surface of the heater with a layer of flowing air so that the heat is not all radiated at one spot in the vicinity of the heater but is absorbed by the flowing medium and distributed by convection to the parts from which the cold air is withdrawn. By providing the fire pot with an outlet-opening of unrestricted area the products of combustion are permitted to issue freely therefrom and to play with full intensity upon the tubular flues, and the absence of curves and inaccessible recesses on the floor of the combustion box makes it possible to easily and completely remove soot from said combustion box by way of the clean-out door. The blanket of air surrounding the combustion box acts as a heat insulation, making it perfectly safe to install the heater adjacent walls and floors of a non-fireproof nature, so that the maintenance of the heater in living rooms entails no increase in the fire risk. The concealed location of the cold air flues, beneath the heater adapts it for use in rooms where utilitarian articles should possess some of the attributes of ornamentation, and the convenient arrangement of the humidifier with the signal cooperating therewith, makes more certain the use of a device which is necessary for healthful heating of living rooms, attention to which in heaters of the usual type has heretofore usually been neglected on account of its inaccessibility.

It is obvious that the specific details of construction and configuration of parts described herein may be modified in various ways without sacrificing the advantages of the invention or departing from the scope thereof as defined in the appended claim.

Having described my invention what I claim as new and desire to secure by Letters Patent, is:—

A heater comprising an outer casing, a combustion box within said casing and spaced from the walls thereof forming an enveloping air chamber, an open topped fire pot in the forward part of said combustion box, a plurality of banks of vertical flues arranged rearwardly of said fire pot and communicating at their opposite ends with said enveloping air chamber, a smoke pipe leading from the rear part of said combustion box, a vertical partition arranged intermediate said banks of flues and between said fire pot and smoke pipe for deflecting the heated products of combustion longitudinally of said flues, said partition having a damper controlled draft opening at its upper end, a grating constituting the upper wall of said air chamber and extending above said fire pot and said flues and cold air supply conduits communicating with that part of said enveloping air chamber which lies directly beneath said banks of flues.

In testimony whereof I have hereunto set my hand in presence of two subscribing witnesses.

CORYDON W. SEXTON.
